UNITED STATES PATENT OFFICE

ADAM F. HOFF, OF BALTIMORE, MARYLAND

CATAMENIAL SACK

Application filed May 6, 1927. Serial No. 189,362.

This invention relates to novel improvements in catamenial sacks or bandages provided with a detachable pad, especially designed to furnish safety and more comfort 5 to the wearer, and to provide against the soiling of the clothing during the menstrual period.

The prime object of the invention is to provide a simple, durable, and economical catamenial sack or bandage and a detachable pad possessing the maximum amount of comfort and protection to the user thereof.

A further object is to construct my improved catamenial sack and a detachable pad 15 so that it will be properly and safely supported during its use, and that it will prevent any and all leakage of the menstrual discharge thereby preventing the soiling of the underwear.

20 Another object of the invention is to so construct the sack or bandage that it will absorb all perspiration, and prevent sticking or adhering to the person while in use.

The foregoing and such other objects as 25 may appear from the ensuing description are accomplished by the construction, arrangement, location and combination of the several parts, hereinafter more fully described, illustrated in the accompanying drawings, 30 and particularly pointed out in the claims appended hereto, it being understood that slight changes in the precise form, proportions and minor details of construction may be resorted to without departing from the 35 spirit or sacrificing any of the advantages of the invention.

In the accompanying drawings forming a part of this specification it will be seen that:

40 Figure 1 is a side elevation of the catamenial sack or bandage embodying my invention.

Fig. 2 is a transverse section taken in the plane of the dotted line 2—2, Fig. 1.

45 Fig. 3 is a plan view of the device shown in Fig. 1.

Fig. 4 is a side elevation of the absorbent pad removed from the supporting sack or bag.

50 Fig. 5 is an inverted plan of the pad shown by Fig. 4, and

Fig. 6 is a plan view of the supporting member detached or removed from the sack or bag, shown broken away at each end thereof.

In the embodiment of my invention as illustrated the numeral 1 designates the top covering of the pad member which is made of any suitable absorbent material, said covering terminating at each end in a flattened portion resting in contact with a supporting member 2, said top covering being fixedly formed with a laterally extending overlapping depending portion 3 at each side of a downwardly extended sack or bag, each depending portion being filled with suitable absorbent cotton or other desirable absorbing material, said pad member being formed with a central depending portion 3' also filled with suitable absorbing material, said central depending portion being removably fitted within the sack or bag as hereinafter described.

It will be perceived that I provide a sack or bag 4 formed preferably of suitable waterproof material within which is disposed the specially formed pad, the outer face of the pad being formed of any suitable fabric 5 which is filled in with absorbent cotton or any other desirable fibrous absorbing material, said pad having an unobstructed smooth flat portion and being stitched through at different points intermediate its length and width to prevent the shifting of the fibrous absorbent material during use as is clearly shown in Figs. 4 and 5 of the drawings.

The outer face of the waterproof material sack or bag is suitably covered with a silk or other desirable soft material 6, adapted to comfortably contact with the skin of the 90 wearer, and serving the double purpose of absorbing all perspiration and at the same time preventing the sticking or adhering of the sack to the skin or flesh of the user, or said absorbent means 6 may be permanently 95 attached to the outer facing of the sack or bag or made an integral part of said outer facing of sack by a suitable treatment.

The supporting member 2 is composed of any suitable material possessing the required 100

strength, and which serves to connect both sides of the waterproof sack or bag to the usual belt which surrounds the body of the wearer, and is so constructed that it will rest against the body of the wearer in a flattened condition when in use. Said member 2 also serves as a frame support of the waterproof sack and also serves to retain the sack in its proper position and relieve said sack or bag of all strain while in use. For this purpose the member 2 is provided with a central opening in the form of a slit, and has two side portions 8 to which the mouth of the sack is attached. The sides 8 are of flexible material, and form a continuation of the ends of said member 2. The said sides 8 are fixedly secured to the mouth of the sack in a vertical position, such as is clearly shown in Fig. 2 of the drawings, thereby assuring a flattened position of the sack when it comes into contact with the wearer, and thus imparts much comfort to said wearer.

It will be readily obvious that by the construction hereinbefore described the discharge will be absorbed by the overlapping portions and the central portion of the pad; that the sack or bag will retain all the excessive discharge, and prevent its leaking out and soiling the clothing of the wearer; that the absorbent pad will always be rigidly held in its proper position; that the absorbent material will always be retained within the removable pad in its proper position, and that the outer absorbent facing of the sack will take up all perspiration, prevent any sticking or clinging to the flesh or skin, and add materially to the comfort of the wearer.

Having thus described my invention what I claim and desire to secure by Letters Patent is:

1. In a catamenial device, the combination of a sack of waterproof material with an outer surface of absorbent material, a detachable pad disposed within said sack, said pad having a smooth flat top portion and a fixed laterally extending and downwardly depending portion at each side thereof, means whereby the opposite sides of the pad member are fastened together at different points intermediate its length and width, and flexible supporting means disposed at each side of said sack.
2. In a catamenial device, the combination of a sack having an outer surface of absorbent fabric, a removable pad member disposed within the sack and provided with lateral overlapping edges and a central depending portion fitted within said sack, said pad terminating with a flattened portion at each end, and a supporting member secured vertically at each side of the said sack.

ADAM F. HOFF.
